UNITED STATES PATENT OFFICE.

JOHN F. FORD, OF BALTIMORE, MARYLAND, ASSIGNOR OF ONE-HALF TO
WARREN H. SADLER, OF SAME PLACE.

ACETYLENE-GAS GENERATOR.

SPECIFICATION forming part of Letters Patent No. 669,938, dated March 12, 1901.

Application filed May 31, 1900. Serial No. 18,559. (No model.)

To all whom it may concern:

Be it known that I, JOHN F. FORD, a citizen of the United States, residing at Baltimore, State of Maryland, have invented certain new and useful Improvements in Acetylene-Gas Apparatus, of which the following is a specification.

My invention relates to apparatus for the production of acetylene gas; and its object is to provide apparatus of this character which will automatically control the production of gas according as the supply is used, which will embody few and simple parts not requiring any especial attention or oversight and not liable to get out of order, and which will be entirely safe.

The invention consists in certain arrangements, constructions, and combinations of the parts, which I shall hereinafter fully describe, and particularly point out in the appended claims.

Reference is to be had to the accompanying drawings, in which—

Figure 1 is a perspective view of the apparatus. Fig. 2 is a vertical longitudinal section thereof. Fig. 3 is a detail plan view, on an enlarged scale, of the grate which supports the carbid. Fig. 4 shows three views illustrating the shell which fits over the grate and forms therewith the carbid-holder. Fig. 5 is a detail sectional and a plan view of the casting and cylinder which supports the grate. Fig. 6 is a side elevation of the lower portion of the generator looking in the direction indicated by the arrow *x*, Fig. 1; and Fig. 7 shows detail views illustrating the stop for the generator-bell and its supporting-collar detached.

The generator of the apparatus comprises a cylindrical water-reservoir *A*, having an inclined bottom *a*, from which leads a discharge-pipe *a'*, and an inturned annular rim *c* at its top. Extending vertically up through the bottom and center of the water-reservoir *A* is a gas-feed pipe *d*, open at its upper end and its lower end connected by an elbow to a pipe *d'*, which enters the gasometer-tank *B*. Around the lower portion of the feed-pipe *d* and resting on the inclined bottom *a* is a tube *e*, on whose upper end rests an open-grated casting *C*, (shown in detail in Fig. 5,) said

grated casting having a central collar *f*, encircling the gas-feed pipe *d*, and a set-screw *f'*, by which it is clamped in place. A reticulated screen *g*, preferably of woven wire, 55 covers the grated casting *C*, and to the rim of the latter an upwardly-extending cylinder *h* is suitably secured. The grated casting is further formed with an annular flange *i*, encircling its collar *f*, and an open-ended cylinder *j*, smaller than the cylinder *h*, fits around said flange, by which it is kept from lateral displacement, and supports at its upper end a grate *D*, which supports the charge of carbid. This grate consists of a plurality of spaced- 60 apart concentric rings *k*, (see Fig. 3,) joined together by radial webs *k'*, which at their inner ends surround the vertical tube *m*, running through the center of the carbid-holder shell. On each ring and radial web are a number of 65 vertical prongs *l*, terminating in the same horizontal plane, on which the carbid directly rests, so that the water may obtain ready access to the carbid and that the ash may more readily drop away, leaving the contact-surface of the grate clean, and any small particles of carbid which may drop through the grate *D* will be caught by the wire screen *g* and retained until entirely exhausted, when the residuum or ash will fall through the 70 screen onto the inclined bottom *a* of the reservoir and can be drawn off by means of a faucet attached to discharge-pipe *a'*.

The holder for the carbid comprises the grate *D*, described above, which forms the 75 bottom of the holder, in combination with a vertically-movable cylindrical shell *E*, (shown in detail in Fig. 4,) which is open at its bottom and fits loosely around the grate *D* to form the sides and top of the carbid-holder, 80 being provided with a central guiding-tube *m*, attached to the cover of the shell and fitting down over the gas-feed pipe *d*, and the sides of the shell are formed with one or more series of slots *n*, which overlap each other and 85 through which the gas may flow, while the cover of the shell is provided with openings *o*, through which the carbid is inserted to fill the holder.

When it is desired to charge the holder, the 90 grate *D* and shell *E* are together slipped upwardly off the gas-feed pipe *d*. The carbid

is then inserted through the openings o in the cover until the holder is filled. The grate and shell are then together inserted in place over the gas-feed pipe d until the grate rests 5 on top of the small cylinder j . The shell will then be supported by its cover resting upon the carbid.

F designates a water-displacing generator-bell which fits snugly but loosely within the 10 inturned annular rim c of the water-reservoir A and down over the carbid-holder and cylinder h , which latter helps to guide the bell in its up-and-down movements, and said bell is provided with an annular partition p , 15 spaced from its top and forming, with the latter, a dead-air chamber p' . A central tube q extends up inside the said dead-air chamber and is adapted to fit down loosely over the upper end of the gas-feed pipe d when the 20 bell descends.

The upward movement of the generator-bell F is limited by a stop G, (shown in detail in Fig. 7,) which is formed with a central collar r , loosely fitted on a vertical auxiliary 25 escape-pipe H, which will be hereinafter described, said collar having an angular notch s on its lower side and two oppositely-extending arms t . A sleeve u fits around said auxiliary escape-pipe H, below the stop G, and is 30 provided with a set-screw u' , to impinge against the pipe, and an inclined upper edge s' , adapted to fit in the said angular notch and support the stop G. One or the other of the arms t , owing to the peculiar angular arrangement of the notch s and the inclined upper edge s' , will always automatically extend into the vertical path of movement of the bell F and engages the top of the bell to stop the same, and it is obvious that upward 35 pressure on one arm only will not raise the stop, but will cause it to bind on the pipe and remain rigidly in place; but when it is desired to raise the generator-bell F for the purpose of removing it the stop G will be raised 40 by hand and turned around on the auxiliary escape-pipe H, so as to place the arms t out of the way of the bell.

In order to determine at any time the height of the column of carbid in the holder, I have 45 provided a movable measuring-rod J, guided vertically in the water-reservoir A. The upper end projects above the top of the reservoir and below has a returned end v , extending up inside the bell F and adapted to contact with the bottom of the shell E, so that the position of the shell, and consequently the height of the carbid, may be determined.

The gasometer of the apparatus comprises a separate water-tank B, preferably permanently connected with the water-reservoir A by one or more webs v' and having an inturned annular rim c' , in which fits snugly but loosely the gasometer-bell I, which is attached to a central open-ended safety-pipe e' , slidably surrounding a vertical stationary guide-rod f^2 .

The safety-pipe e' has its upper end e^3 extending outside the top of the bell and is

adapted to slide into a sleeve e^3 , depending from a coupling g' , from which leads a main escape-pipe K, adapted to discharge the gas 70 into the open atmosphere outside the building in which the apparatus is located.

The gas-pipe d' , which leads from the generator and enters the gasometer-tank B, is connected by a T-joint to a vertical gas-pipe 75 d^2 , which extends up inside the bell I, and at its upper end is provided with a returned portion d^3 , having a downwardly-opening mouth. A looped wire e^4 extends across said mouth, and a stem e^5 on a ball-valve L extends loosely upwardly through the loop in the wire e^4 and has a head h' , which retains the ball-valve in its proper relation to the mouth of the pipe. On the vertical pipe d^2 , adjacent the mouth of the said returned portion d^3 , is secured a supporting-sleeve j' , to which an angular arm k^2 is pivoted, and the free end of said arm is provided with a roller-float M, which being in the water is adapted to raise the arm k^2 against the ball-valve L 80 and force the valve to its seat, and thereby cut off the inflow of gas when the latter raises the bell I nearly to the upward limit of its movement. When the bell I descends, its lower edge engages the float M and presses 85 it down, and it rolls along the inner side of the bell in a depressed position, thus permitting the gas to force past the ball-valve L. The ball-valve L being lighter than the water and always submerged is normally held 90 to its seat by the upward pressure of the water, but so lightly that the gas coming from the generator will force past the ball-valve and pass through the water into the gasometer-bell I. When the gasometer-bell I rises 95 sufficiently to allow the float M to also press upon the ball-valve L, the pressure of the gas coming from the generator-bell is no longer sufficient to force past the ball-valve, and the gas must therefore remain in the generator. The gas which is thus kept back in the generator forces the level of the water in the generator down below the level of and out of contact with the carbid, and consequently 100 the generation of gas ceases until some of the stored-up gas is used and the gasometer-bell I falls, so as to relieve the pressure of the float M on the ball-valve and allow the gas to flow from the generator. The safety-pipe 105 e' is of such length that its lower end will be above the level of the water in the gasometer-tank B when the gasometer-bell I is at the upward limit of its movement, which will permit the gas in the said bell to then enter the lower end of said escape-pipe and rise through 110 the same.

In order to manually depress the float M for the purpose of opening the valve L and allowing all the gas to flow out of the pipe d^2 115 d^3 into the bell I and up through the safety-pipe e' when the bell I is at the upward limit of its movement, I provide a depressor-rod N, bent at its upper end n' and guided through two apertures in the rim c' of the gasometer-

tank and provided at its lower end with a foot n^3 , adapted to engage with the said float M , for the purpose just stated.

The gas is drawn off for service from the 5 gasometer through the pipes P and P' , and all the water-vapor which may be condensed in said pipes is collected in a curved or trapped branch pipe p^2 , immersed in a bucket p^3 . At the point where the lower end of the rod f^2 is 10 connected there is no communication between the horizontal pipes d' and P' , as shown in Fig. 2 in section.

The auxiliary escape-pipe H at its upper 15 end is connected to the main escape-pipe K by means of the coupling g' , and its lower end opens into a gas-and-water trap R , which, as best shown in Fig. 6, consists of a pipe r' , depending from the gas-pipe d' and extending laterally, as at r^2 , and terminating in an 20 upwardly-projecting nozzle r^3 , which has a flaring cup r^4 secured around it, the open end of said nozzle being inserted in the lower open end of the said auxiliary escape-pipe H . The cup r^4 and pipes r' and r^2 are always kept 25 filled with water to form the trap. A cross-pipe w connects the said pipe H with the gas-pipe d' and is provided with a stop-cock w' , as shown, which is opened to permit the egress or ingress of air from or to the bell F , through 30 the pipe H , when it is desired to insert the bell in the water or to raise the generator-bell out of the water. The stop-cock w' is, however, normally kept closed.

The gas-and-water trap R is provided to 35 catch all the water-vapor which may condense in the pipes d , d' , and d^2 and also for use in the following-described emergency: Should it ever happen that the generator-bell F is at the upper limit of its movement and the ball- 40 valve L will not open to permit the gasometer-bell I to rise to its limit and the gas to escape through the safety-pipes e' and K , then the gas will overcome the pressure of the water in the trap (pipes r' r^2 and cup r^4) and 45 pass out of nozzle r^3 and will bubble up through the auxiliary escape-pipe H , so that the water around the two bells F and I will not overflow.

The water-reservoir A and gasometer-tank B are provided with water-inlet openings b and b' near their upper rims and near the point of their connection with each other, and a plate T extends from the reservoir to the gasometer-tank at this point and forms 55 a funnel, into which the water may be poured, one stream of water entering the reservoir and another entering the tank, so that both will be supplied with water to the same height.

In practical operation, the carbid-holder 60 being full and the generator-bell F resting on top of the shell E , water is poured into the water-funnel T until it reaches the level outside the generator-bell F and gasometer-bell I , (indicated by the line 10 10, Fig. 2.) Then 65 the water inside the generator-bell F will rise and attack the carbid, and as soon as gas is

generated the weight of the bell F will be lifted off the top of the shell E and will displace the water inside of the bell and cause its level to recede to the point indicated by the 70 line 20 20, same figure. At this point the water will not come in contact with the carbid, while the gas which has been generated will pass to the gasometer. The displacement of the water inside the generator-bell 75 F will be maintained so long as said bell is out of contact with the top of the shell. As the carbid is being used up the shell E will gradually sink down over the grate and will always rest on top of the carbid. When the 80 gas in the generator-bell F has been drawn off, the bell will sink until it again rests on top of the shell E , (which will at this time be at a slightly-lower point,) and the displaced water will again rise to attack the carbid. 85 It will thus be seen that the generator-bell F as it moves into and out of contact with the top of the shell E will automatically control the generation of the gas according to the 90 consumption of the same, and when all the carbid has been used up the top of the shell E will rest directly on the carbid-grate D , the bell F will rest on top of the shell, and the water will rise to about the point indicated by the line 30 30 and cause practically 95 all the gas left within the bell F to be driven over into the gasometer. Moreover, it will be seen that there is a water connection between the water-reservoir A and water-tank B by means of the funnel formed by the plate 100 T and openings b b' , and should the pressure of gas in the generator become so great that it tends to force the water out of the reservoir A said water will flow out of the opening b over into the tank B and will not run 105 out on the floor.

Having thus described my invention, what I claim as new, and desire to secure by Letters Patent, is—

1. In an acetylene-gas apparatus, the combination of a water-reservoir; a grate adapted to support the carbid and immovably held in said reservoir; a shell slidably fitted over said grate and adapted to be supported by the carbid; and a water-displacing bell inserted over 110 said shell.

2. An acetylene-gas generator, comprising a water-reservoir; a vertically-movable bell in said reservoir; and a carbid-holder within said bell at such an elevation as to hold the 115 carbid above the level of displacement, whereby when the gas is withdrawn from the bell the latter will descend and rest on the top of the holder and allow the water to rise above the level of displacement and attack the carbid. 125

3. In an acetylene-gas generator the combination of a water-reservoir; a water-displacing bell in said reservoir; and a vertically-telescoping carbid-holder within said bell and on which the bell is adapted to rest when the 130 gas is withdrawn therefrom, whereby to restore the displacement of the water.

4. An acetylene-gas generator comprising a water-reservoir; a grate for the carbid supported within said reservoir; a casting below said grate and provided with a screen and an upwardly-extending cylinder h ; and a water-displacing bell fitting down over said grate and cylinder and guided in its movements by the latter.

5. An acetylene-gas generator, comprising a water-reservoir having a gas-feed pipe leading therefrom; a screen-covered casting fitted on said feed-pipe and having a cylinder h extending upwardly from around its outer edge and a central annular flange; a smaller cylinder resting around said annular flange; a grate for the carbid resting on said last-named cylinder; a shell slidably fitted over said grate and adapted to be supported by the carbid; and a water-displacing bell over said shell.

6. An acetylene-gas generator comprising a water-reservoir having a gas-feed pipe leading from its bottom; a tube fitted around said pipe and resting on the bottom of the reservoir; a screen-covered casting having a collar fitted around said feed-pipe, an annular flange encircling said collar, and an upwardly-extending cylinder surrounding said flange—said casting resting on the said tube; an open-ended cylinder fitted around the said annular flange; a grate for the carbid resting on said last-named cylinder; a shell slidably fitted over said grate and adapted to rest on the carbid, said shell having a central tube slidably fitted on the feed-pipe; and a bell over said shell.

7. An acetylene-gas generator, comprising a water-reservoir having a vertical gas-feed pipe leading therefrom; a grate for the carbid supported by said pipe; a shell slidably fitted over said grate and adapted to be supported by the carbid, whereby when the carbid is used up, the top of the shell will rest on the grate; and a water-displacing bell in said reservoir adapted to rest on the top of the said shell when the bell sinks.

8. In an acetylene-gas generator, a carbid-holder consisting of a grate formed of a plurality of spaced-apart concentric rings and radial webs connecting said rings, the rings and webs being provided with upwardly-projecting prongs on which the carbid is adapted to rest; and a shell slidably fitted over said

grate and having a central tube adapted to extend through said grate, and provided with slotted sides.

9. In an acetylene-gas apparatus, the combination with the generator, gasometer, and gas-pipe arranged to convey the gas from the generator to the gasometer, of a gas-and-water trap consisting of a pipe r' depending from said gas-pipe and having an upwardly-projecting nozzle; a cup t^2 secured around said nozzle—the pipe r' and cup t^2 being adapted to contain water; and a safety-pipe w having its open end fitting over said nozzle and arranged to lead off the gas which escapes from the same.

10. In an acetylene-gas apparatus, the combination with the generator, gasometer, and gas-pipe arranged to convey the gas from the generator to the gasometer, of a gas-and-water trap consisting of a pipe r' depending from said gas-pipe and having an upwardly-projecting nozzle; a cup t^2 secured around said nozzle—the pipe r' and cup t^2 being adapted to contain water; a safety-pipe having its open end fitting over said nozzle inside of the cup and arranged to lead off the gas which escapes from the same; and a bypass pipe w connecting the pipe r' with the safety-pipe and provided with a stop-cock, as and for the purpose set forth.

11. In an acetylene-gas apparatus, a stop for a vertically-movable bell, said stop having oppositely-extending arms one of which is normally located in the path of the bell and an angular notch on its lower side; and a sleeve for loosely supporting said stop formed with an inclined upper edge which fits in said notch, as and for the purpose set forth.

12. In an acetylene-gas apparatus, the combination of the cylindrical generator-tank and gasometer-tank closely connected together and each provided with a water-inlet opening near the point of their connection; and a plate extending from the generator-tank to the gasometer-tank and serving as a funnel for said water-inlet openings, as set forth.

In testimony whereof I affix my signature in the presence of two witnesses.

JOHN F. FORD.

Witnesses:
